UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

METAL STRUCTURE FOR RAILWAY CARS.

Application filed October 9, 1922. Serial No. 595,634.

My invention relates to the construction of railway cars and more particularly to metal end structures or walls for railway cars made of one or more metallic plates or panels 5 formed with integral reinforcing, stiffening and bracing corrugations or embossments. However, this device may be incorporated in the construction of car side walls, floors, roofs or doors used in connection with railway cars 10 of various types.

It is well known that the end walls of railway cars are more likely to be broken or otherwise injured than the side walls. This is due to the inertia thrusts and pressures caused by 15 the shifting of the cargoes when the train starts or stops. These thrusts may be local, tending to distort the end in some particular spot, as, for example, when a piece of piping or lumber shifts lengthwise imparting a blow 20 against the end wall of the car; or there may be a general tendency to break out the end wall as a whole or tear it away from the framing. For the purpose, therefore, of greater strength and durability, car ends have been 25 constructed of metal plates corrugated or formed with ribs to impart the desired strength, rigidity and resiliency.

One of the principal objects of my invention is to provide a corrugated or embossed 30 metallic end structure for railway cars in which the corrugations or embossments have a configuration and arrangement that impart to the structure a maximum capacity for resisting cargo thrusts, both local and general 35 static or quiescent, and with sufficient resiliency to prevent permanent distortion due to the thrusts of the loads, with a minimum weight of metal. It is important that structures of this sort should be as light as is possible, consistent with strength and durability, 40 both for reasons of economy in manufacturing cost and also to keep the weight of the car at a minimum.

A further object is to provide a corrugated 45 metallic wall element that is practically possible to manufacture. A further object is to provide a metallic wall element with corrugations or embossments that resist to a greater degree torsional stresses, as well as 50 brace the element, and the car end against diagonal side thrusts or weaving. Another object is to form a metallic plate with integral corrugations or ribs which impart to it a cer-

tain amount of strength and rigidity to resist loads imposed thereon and to so form the ends 55 of the corrugations or ribs as to provide a certain amount of resiliency to enable the plate to deflect and return to its normal position without appreciable amount of permanent distortion. 60

Like characters of reference designate like parts.

The end wall structure shown in the above

figures comprises a panel composed of a corrugated metal plate or plates.

Referring to Figs. 1 and 2, the corrugated plates 1, 2 and 3 extend across the car from side to side and are formed with integral flanges 4 along the vertical edges which overlap and are secured to the frame members of the side walls 5 of the car by any suitable means.

- 14 The top edge of the end wall is secured beneath the fascia boards 7 and the meeting edges of the plate overlap and are secured together by rows of rivets 8 and the lower edge of the end wall is secured to the end sill 9.
- 15 Nailing strips 10 are secured to the plates 1, 2 and 3 by bolts and lining 11 is secured to the nailing strips 10.

Figs. 3 and 4 show the invention applied to a gondola type of car, wherein only one plate 12 is used to form the end panel which extends from side to side of the car and is provided along the vertical edges with flanges 13 which overlap and are secured to the frame members of the side walls 14 by any suitable means. The top edge of the plate is secured to the top chord 15 by rivets 16, while the lower edge is secured by rivets 17 to the end sill 18.

While the corrugations are shown pressed outwardly, and in horizontal arrangement, it is understood that the corrugations or embossments may be pressed inwardly or partially inwardly and partially outwardly from the original plane of the plate or the corrugations or embossments may be placed in any position for instance vertically or diagonally. The plates or panels may be positioned vertically or horizontally and applied to any type of railway car.

40 Figs. 5 to 9 inclusive show the preferred form wherein the plate is provided with a plurality of parallel embossments, each embossment comprising a plurality of sinuous minor corrugations 20 formed therein which are spaced apart distances substantially equal to their respective widths and the part of the plate between adjacent minor corrugations is also sinuous so that these minor corrugations merge together to form a contiguous sinuous 45 configuration symmetrical in cross section about a line midway between the outermost portions of these minor corrugations so that this line is the neutral axis of the section. Such a section is very resilient and has a 50 spring like action under loads, and, furthermore, produces a very strong section for the amount of metal used. These minor corrugations merge into the plane of the plate by means of terminal portions of any desired 55 formation. A plurality (two or more) of such minor corrugations 20 merge together between their ends or preferably adjacent the middle of the plate (or middle of the embossment comprising the minor and major corrugations) to form a lesser number of major 60

corrugations 21 with preferably flat apices 25 which are spaced apart distances substantially equal to their respective widths and the part 26 of the plate 24 between these major corrugations is also preferably flat, thus forming a configuration symmetrical in cross section about a line midway between the outermost portions of these major corrugations so that this line is the neutral axis of the section. Such a section is stronger and relatively rigid 70 as compared with the section of the sinuous minor corrugations because more metal is positioned away from the neutral axis. By such an arrangement a corrugated metallic plate is provided which is relatively rigid adjacent the middle portion of the embossments and relatively resilient adjacent the opposite end portions of the embossments. The secondary oppositely projecting rib or corrugation 22 formed by the merging of the two adjacent minor corrugations 20 is equal in width to the adjacent minor corrugations at 23 and decrease in width as the minor corrugations merge together to form the major corrugation 21. These secondary oppositely projecting ribs 22 also preferably decrease in depth so that any concentrated stretch of metal is eliminated where the minor corrugations merge together. 90

95 Figs. 10, 11 and 12 are detail enlargements of portions of the plate taken on lines 7, 8 and 9, respectively, of Fig. 5 showing the flat apex 25 of the major corrugation (Fig. 10) split or divided by the secondary corrugation 22 into two contiguous sinuous corrugations 20 (Fig. 12).

100 Figs. 13, 14 and 15 are detail enlargements of a modified form of corrugation similar to Figs. 10, 11 and 12, respectively, wherein the apex (29) of the major corrugation is arcuate. 105

Figs. 16 to 20 inclusive show a modification wherein the embossments have parallel sides.

110 Figs. 21 to 25 inclusive are similar to Figs. 5 to 9 inclusive except that they illustrate three minor corrugations merging into a single major corrugation.

115 Figs. 26 to 30 inclusive show a modified form wherein the major corrugations 31 have arcuate or sinuous apices 30 and the portion of the plate 31 between adjacent embossments is also arcuated or sinuous.

120 The major corrugations are preferably of uniform width for a short distance at the center of the plate to provide greater strength for a wider portion of the plate and also to facilitate changing the forming dies when it is desired to increase or decrease the length of the corrugations or embossments. (See Fig. 26.)

125 Plates provided with a plurality of contiguous narrow corrugations possess a considerable amount of elasticity and when struck a blow deflect readily and regain their shape without distortion, whereas a plate provided with wide flat corrugations, though bet- 130

ter able to carry quiescent loads, has not the resiliency of the former and is more readily distorted when struck a blow.

It is, therefore, desirable to design a plate 5 that possesses great strength to withstand the sudden impact load blows with sufficient resiliency to resist distortion.

The particular form and advantages of the 10 terminations of the corrugations illustrated in Fig. 5 are not described or claimed specifically herein, but are described and claimed in my Patent No. 1,547,831 dated July 28, 1925, for corrugated wall elements.

This application is confined to the construction 15 wherein the minor corrugations merge to form the major corrugations, while my application Serial No. 595,632, filed October 19, 1922, for corrugated metallic wall elements covers the construction wherein the major 20 corrugation is split into two or more minor corrugations.

The accompanying drawings illustrate the preferred form of the invention, though it is to be understood that the invention is not limited to the exact details of construction shown 25 and described, as it is obvious that various modifications thereof within the scope of the claims will occur to persons skilled in the art.

What I claim is:

30 1. A metallic wall panel for railway cars having a reinforcement formed therein, comprising a plurality of stiffening ribs which merge into each other to form a relatively wider stiffening rib, adjacent the center of 35 said reinforcement substantially parallel to the first mentioned ribs.

2. A metallic panel for a railway car structure having a plurality of reinforcements formed therein with their longitudinal axes 40 substantially parallel, the ends of said reinforcements and the parts of the panel between them comprising tension and compression members substantially equal in width 45 connected by webs spaced substantially equi-distant apart, a plurality of said reinforcements merging into each other adjacent their centers so that said reinforcements and the parts of the panel between them comprise relatively wider tension and compression members 50 substantially equal in width connected by webs spaced substantially equi-distant apart.

3. A metallic panel for a railway car structure having a plurality of reinforcements 55 formed therein with their longitudinal axes substantially parallel, the ends of said reinforcements and the parts of the panel between them comprising tension and compression members substantially equal in width connected by webs spaced substantially equi-distant apart, a plurality of said reinforcements merging into each other adjacent their centers so that said reinforcements and the parts of the panel between them comprise relatively 60 wider tension and compression members sub-

stantially equal in width connected by webs spaced substantially equi-distant apart, the height of said reinforcements remaining constant the major portion of their length.

4. A metallic panel for a railway car structure having a plurality of reinforcements formed therein with their longitudinal axes substantially parallel, said reinforcements and the parts of the panel between them comprising tension and compression members connected by webs and reinforcing ribs springing from said tension members between the opposite ends of the reinforcements which gradually increase in depth and in width toward the opposite ends of the reinforcements. 70

5. A metallic panel for a railway car structure having a plurality of reinforcements formed therein with their longitudinal axes substantially parallel, said reinforcements and the parts of the panel between them comprising tension and compression members connected by webs and reinforcing ribs springing from one of said members between the opposite ends of the reinforcements which gradually increase in depth and in width toward the opposite ends of the reinforcements. 75

6. A metallic plate provided with a plurality of corrugations terminating adjacent the edges thereof that merge into a lesser number of corrugations adjacent the center of said plate substantially parallel to the first mentioned corrugations. 80

7. A metallic plate provided with a plurality of major and minor corrugations, uniform and contiguous at their ends, adjacent the edges of said plate and merging into a lesser number of major corrugations adjacent their centers, the major corrugation being struck out parallel with the original plane of the plate, with the minor corrugations pressed in 90 opposite direction within the major corrugation and at an angle to the original plane of the plate. 100

8. A metallic plate provided with a plurality of uniform contiguous corrugations at 110 their ends adjacent the edges of said plate that merge into a lesser number of larger corrugations adjacent the center of said plate.

9. A metallic plate having a plurality of corrugations terminating within said plate 115 that merge into a lesser number of larger corrugations at the center of said plate substantially parallel to the first mentioned corrugations.

10. A metallic plate having a plurality of corrugations terminating within said plate that merge into a lesser number of larger corrugations at the center of said plate, the cross sectional area of said corrugated plate being substantially equal anywhere between the 125 planes where said corrugations begin to terminate into the plane of said plate.

11. A metallic plate wall panel having a plurality of reinforcements formed therein, spaced apart distances substantially equal to 130

- their width, said reinforcements having parallel sides for their entire length and comprising a plurality of stiffening ribs which merge into each other adjacent the center thereof to form a relatively wider stiffening rib.
12. A metallic plate provided with a plurality of corrugations spaced apart distances substantially equal to their width, said corrugations merging between their ends into a lesser number of corrugations spaced apart distances substantially equal to their width.
13. A metallic plate provided with a plurality of corrugations spaced apart distances substantially equal to their width, said corrugations merging between their ends into a lesser number of wider corrugations spaced apart distances substantially equal to their width.
14. A metallic plate provided with a plurality of corrugations merging adjacent the middle of the plate into a lesser number of wider corrugations substantially parallel to the first mentioned corrugations.
15. A metallic plate provided with a plurality of corrugations symmetrical in cross section about a line midway between the outermost portions of the corrugations, said corrugations merging between their ends into a lesser number of corrugations symmetrical in cross section about a line midway between the outermost portions of the corrugations.
16. A metallic plate provided with a plurality of corrugations symmetrical in cross section about a line midway between the outermost portions of the corrugations, said corrugations merging between their ends into a lesser number of wider corrugations symmetrical in cross section about a line midway between the outermost portions of the corrugations.
17. A metallic plate provided with a plurality of corrugations of constant cross section for a short distance at the center of the plate which diverge into a greater number of corrugations adjacent the edges of the plate.
18. A metallic plate provided with a plurality of sinuous corrugations, said corrugations merging adjacent the middle of the plate into a lesser number of corrugations with substantially flat apices.
19. A metallic plate provided with a plurality of sinuous corrugations, said corrugations merging adjacent the middle of the plate into a lesser number of wider corrugations with substantially flat apices.
20. A wall for a railway car comprising a metallic plate secured to oppositely disposed frame members of the car, said plate provided with a plurality of corrugations with their opposite ends terminating into the plate adjacent said oppositely disposed frame members, said corrugations merging together adjacent the middle of the plate to form a lesser number of wider corrugations.
21. A wall for a railway car comprising a metallic plate secured to oppositely disposed frame members of the car, said plate provided with a plurality of corrugations spaced apart distances substantially equal to their width with their opposite ends terminating into the plate adjacent said oppositely disposed frame members, said corrugations merging together between their ends to form a lesser number of corrugations spaced apart distances substantially equal to their width.
22. A wall for a railway car comprising a metallic plate secured to oppositely disposed frame members of the car, said plate provided with a plurality of corrugations spaced apart adjacent their ends distances substantially equal to their width with their opposite ends terminating into the plate adjacent said oppositely disposed frame members, said corrugations merging together between their ends to form a lesser number of wider corrugations spaced apart distances substantially equal to their width.
23. A wall for a railway car comprising a metallic plate secured to oppositely disposed frame members of the car, said plate provided with a plurality of corrugations symmetrical in cross section about a line midway between the outermost portions of the corrugations with their opposite ends terminating into the plate adjacent said oppositely disposed frame members, said corrugations merging together between their ends to form a lesser number of corrugations symmetrical in cross section about a line midway between the outermost portions of the corrugations.
24. A wall for a railway car comprising a metallic plate secured to oppositely disposed frame members of the car, said plate provided with a plurality of corrugations symmetrical in cross section about a line midway between the outermost portions of the corrugations with their opposite ends terminating into the plate adjacent said oppositely disposed frame members, said corrugations merging together between their ends to form a lesser number of wider corrugations symmetrical in cross section about a line midway between the outermost portions of the corrugations.
25. A wall for a railway car comprising a metallic plate secured to oppositely disposed frame members of the car, said plate provided with a plurality of corrugations with their opposite ends terminating into the plate adjacent said oppositely disposed frame members, said corrugations merging together adjacent the middle of the plate to form a lesser number of corrugations which are of constant cross section for a short distance at the middle of the plate.
26. A wall for a railway car comprising a metallic plate secured to oppositely disposed frame members of the car, said plate provided with a plurality of corrugations with

- their opposite ends terminating into the plate adjacent said oppositely disposed frame members, said corrugations merging together adjacent the middle of the plate to form a 5 lesser number of wider corrugations which are of constant cross section for a short distance at the middle of the plate.
27. A wall for a railway car comprising a metallic plate secured to oppositely disposed frame members of the car, said plate provided with a plurality of sinuous and contiguous corrugations with their opposite ends terminating into the plate adjacent said oppositely disposed frame members, said corrugations merging together between their ends to form a lesser number of corrugations with substantially flat apices. 10
28. A wall for a railway car comprising a metallic plate secured to oppositely disposed frame members of the car, said plate provided with a plurality of sinuous and contiguous corrugations with their opposite ends terminating into the plate adjacent said oppositely disposed frame members, said corrugations merging together between their ends to form a lesser number of wider corrugations with substantially flat apices. 15
29. A metallic plate provided with a plurality of sinuous corrugations with the parts 20 of the plate between said corrugations also of sinuous configuration, said corrugations merging together between their opposite ends to form a plurality of fewer corrugations having substantially flat apices.
30. A metallic plate provided with a plurality of sinuous corrugations with the parts 25 of the plate between said corrugations also of sinuous configuration, said corrugations merging together between their opposite ends to form a plurality of fewer wider corrugations having substantially flat apices. 30
31. A metallic plate provided with a plurality of sinuous corrugations with the parts 35 of the plate between said corrugations also of sinuous configuration, said corrugations merging together between their opposite ends to form a plurality of fewer corrugations having substantially flat apices with the parts of the plate between the last mentioned 40 corrugations also being substantially flat.
32. A metallic plate provided with a plurality of sinuous corrugations with the parts 45 of the plate between said corrugations also of sinuous configuration, said corrugations merging together between their opposite ends to form a plurality of fewer wider corrugations having substantially flat apices with the parts of the plate between the last mentioned 50 corrugations also being substantially flat.
33. A metallic panel for a railway car structure having a plurality of reinforcements formed therein with their longitudinal axes substantially parallel, said reinforcements and the parts of the panel between them comprising tension and compression 55 members connected by webs, and reinforcing ribs springing from one of said members between the opposite ends of the reinforcements which gradually increase in depth toward the opposite ends of the reinforcements. 70
34. A metallic plate for a railway car structure having a reinforcement formed therein comprising a plurality of stiffening ribs which merge into each other between their ends to form a relatively wider stiffening rib substantially parallel to the first mentioned ribs. 75
35. A metallic panel formed with a plurality of corrugations that merge between their ends into a plurality of fewer corrugations substantially parallel to the first mentioned corrugations. 80
36. A metallic plate for a railway car structure having a reinforcement formed therein comprising a plurality of stiffening ribs which merge into each other between their ends to form a stiffening rib substantially parallel to the first mentioned ribs. 85
37. A metallic plate formed with a plurality of sinuous embossments with the parts of the plate between the embossments also of sinuous configuration, said embossments merging together between their ends to form a plurality of fewer embossments. 90
38. A metallic plate formed with a plurality of sinuous embossments with the parts of the plate between the embossments also of sinuous configuration, said embossments merging together between their ends to form a plurality of fewer wider embossments. 95
39. A metallic wall structure for a railway car comprising a metallic plate secured to oppositely disposed frame members of the car, said plate provided with a plurality of sinuous corrugations with the parts of the 100 plate between said corrugations also of sinuous configuration, said corrugations merging together between their ends to form a plurality of fewer corrugations having substantially flat apices, said corrugations terminating into the plate adjacent said oppositely disposed frame members. 105
40. A metallic wall structure for a railway car comprising a metallic plate secured to oppositely disposed frame members of the car, said plate provided with a plurality of sinuous corrugations with the parts of the 110 plate between said corrugations also of sinuous configuration, said corrugations merging together between their ends to form a plurality of fewer wider corrugations having substantially flat apices, said corrugations terminating into the plate adjacent said oppositely disposed frame members. 115
41. A metallic wall structure for a railway car comprising a metallic plate secured to oppositely disposed frame members of the car, said plate provided with a plurality of sinuous corrugations with the parts of the 120 plate between said corrugations also of sinu-

- ous configuration, said corrugations merging together between their ends to form a plurality of fewer corrugations having substantially flat apices with the parts of the plate between the last mentioned corrugations also being substantially flat, said corrugations terminating into the plate adjacent said oppositely disposed frame members.
42. A metallic wall structure for a railway car comprising a metallic plate secured to oppositely disposed frame members of the car, said plate provided with a plurality of sinuous corrugations with the parts of the plate between said corrugations also of sinuous configuration, said corrugations merging together between their ends to form a plurality of fewer wider corrugations having substantially flat apices with the parts of the plate between the last mentioned corrugations

also being substantially flat, said corrugations terminating into the plate adjacent said oppositely disposed frame members.

43. A metallic structure for a railway car comprising a metallic plate secured to oppositely disposed vertical frame members of the structure, said plate provided with a plurality of arcuate horizontal corrugations of constant depth with the parts of the plate between said corrugations also of arcuate configuration, said corrugations merging together between their ends to form a plurality of fewer horizontal corrugations having substantially flat apices with the parts of the plate between the last mentioned corrugations also being substantially flat, said corrugations terminating into the plate adjacent said oppositely disposed frame members.

ARTHUR E. SMALL
